TISSUE MILLS, OF HOLYOKE, MASSACHUSETTS, A CORPORATION OF MASSACHU-
SETTS.

PAPER-PACKAGE.

1,146,186.

Specification of Letters Patent. Patented July 13, 1915.

Application filed June 21, 1913. Serial No. 775,123.

To all whom it may concern:

Be it known that I, WILLIAM McCORKIN-
DALE, a citizen of the United States of
America, residing at Holyoke, in the county
5 of Hampden and State of Massachusetts,
have invented new and useful Improvements
in Paper-Packages, of which the following
is a specification.

This invention relates to a paper package
10 and more particularly to a new package for
towels, wrapping paper, toilet paper, and
whatnot which obviates many difficulties
hitherto inherent in such packages and is at
the same time inexpensive, satisfactory, and
15 convenient. It is well known that when
packages of paper are hung up to be de-
tached sheet by sheet it is a somewhat diffi-
cult problem to provide a hanger or support
therefor which shall be sufficiently inexpen-
20 sive to make it commercially practicable and
yet free from numerous disadvantages as,
for instance, a loosening or sagging of the
pack as its size is diminished, the detach-
ment of many sheets where only one sheet is
25 required, and the littering of the floor with
fragments of paper as each sheet is torn from
the pack. All these disadvantages are ob-
viated and removed by my new package.

Other advantages thereof will appear as
30 the following description proceeds.

In the drawings:—Figure 1 is a plan view
of a package of paper punched and cut ac-
cording to this invention; Fig. 2 is a cross-
section of the same upon its medial line;
35 Fig. 3 is a cross-section showing the secu-
ring device attached thereto; Fig. 4 shows a
complete package partly in cross-section
hanging upon the wall; and Figs. 5 and 6
illustrate the partial removal of the paper
40 therefrom sheet by sheet.

The package of paper *a*, preferably rec-
tangular, has adjacent one end a hole *b*
drilled therethrough preferably in the form
of a slot such as shown. Upon either side
45 of the hole are cuts *c* and *d* extending from
the adjacent edge of the pack to a point
substantially below the hole *b*. Through the
hole *b* is then passed a preferably metallic
binding strip *e* which is thereafter bent over
50 and clamped or a flexible binding of fabric
may be used instead of the metallic binding
strip *e*. The device is then hung upon a
prong stud upon a wall or other support *g*.

In operation, the two cuts *c* and *d* make a
55 plane of weakness across the pack below the

hole *b* so that as the paper is torn away sheet
by sheet a small portion thereof *h*, as clearly
shown in Figs. 5 and 6, remains behind the
tearing occurring substantially in a line
joining the bottoms of the two cuts *c* and *d*. 60
Upon the removal of the successive sheets
therefrom, each sheet comes away without
this portion *h* and, furthermore, instead of
dropping and littering up the floor the por-
tion *h* remains firmly bound by the clamping 65
device *e* in precisely the condition in which
it was before. The sheets may therefore be
removed one by one from the first to the last
and neither the support nor the sheets re-
maining behind will be in the least affected 70
by the removal of preceding sheets. What
may be called the supporting portion of the
pack, namely, the portion about the hole *b*
through which the supporting prong *f*
passes, remains in exactly the same position 75
from first to last.

Having now particularly pointed out my
invention but well knowing that many de-
partures and modifications may be made
from the specific form in which I have 80
chosen here to illustrate it without depart-
ing from the scope of the invention which is
more truly bounded and defined by the
claims hereto appended, I claim:—

1. A package of paper towels comprising, 85
a pack of towel sheets provided with an
opening adjacent one end adapted for the re-
ception of a supporting arm, cuts adjacent
said opening to establish a plane of weak-
ness, and a binding passing through said 90
opening and over the adjacent end of the
pack, whereby the pack may be readily in-
serted on a supporting arm, and the portion
of each sheet adjacent said opening is left
behind as the sheet is torn away. 95

2. A package of paper comprising a pack 100
of towel sheets provided with a centrally ar-
ranged opening adjacent the upper end,
adapted for the reception of a supporting
arm and two vertical cuts, one on each side 105
of said opening and extending slightly be-
low the plane of the opening to form a plane
of weakness whereby the portion of each
sheet between the vertical cuts is left behind
as the sheet is torn away, and means to hold
together the portions so left behind.

3. A package of paper towels, comprising,
a pack of towel sheets formed with a cen-
trally arranged aperture adjacent the upper
end adapted to receive a supporting arm, 110

vertical slits formed in said package adjacent said opening extending from the upper end of the package to a position below the plane of said opening, said slits arranged to form a plane of weakness in the package, and a binding strip passing through said opening and over the adjacent end of the pack, whereby the pack may be readily in-

serted on a supporting arm and the portions of said sheets left behind as said sheets are torn away may be held together.

WILLIAM McCORKINDALE.
